UNITED STATES PATENT OFFICE.

VICTOR H. HARBERT, OF CHICAGO, ILLINOIS, ASSIGNOR TO E. PAYSON SMITH, OF CHICAGO, ILLINOIS.

SUPPORT FOR BRAKE HANGERS.

Application filed March 18, 1927. Serial No. 176,394.

My invention relates to supports for pendently securing the hangers of railroad car brakes to the truck frames, and involves the provision of suitable socket forming means, 5 preferably in the form of an extension or arm of such length and thickness as to permit lengthwise slotting for the purpose of producing a hanger link or hanger supporting pin receiving socket; the arm being either 10 integral with or otherwise secured to the truck frame so as to present the socket preferably in a lateral direction and at a point substantially in alignment with the wheels of the truck.

15 The invention also contemplates suitable means whereby the hanger and the hanger supporting pin will be oscillatably held in the socket; said means involving a structure whereby lateral movement of the link hanger 20 or longitudinal movement of the hanger supporting pin is prevented; said means being constructed to permit an interchange of hangers to be made.

The objects and advantages of my invention will be readily apparent from the detailed description of the drawings, wherein:

Figure 1 is a side elevation of my improved arm shown integral with the truck frame (of 30 which a portion is shown partly in section) and provided with my keeper means as employed with a U-shape hanger of which portions are broken away.

Figure 2 is a perspective view of the arm 35 as disclosed in Figure 1; the hanger and keeper means being omitted.

Figure 3 is an end elevation as viewed from the left hand end of Figure 1.

Figure 4 is a perspective view of one member 40 of my improved keeper means.

Figure 5 is a similar view of the complementary member of said means.

Figure 6 is a view substantially similar to Figure 1 showing a modified form of keeper 45 means adapted for use with the continuous link type of hanger.

Figure 7 is a sectional elevation taken on the line 7—7 of Figure 6.

Figure 8 is a horizontal sectional plan view 50 taken on the line 8—8 of Figure 6.

Figure 9 is a perspective view of one member of the modified form of keeper means employed in Figure 6; and

Figure 10 is a similar view of the comple-

mentary member of said modified form of keeper means.

As disclosed in the drawings, my improved support contemplates the use of either type of brake hanger at present in use; namely the U-shape link as shown at 15 in Figure 1, or the continuous link hanger shown at 16 in Figure 6; thus permitting substitution of the one type for the other without necessitating change in the support or keeper means.

The exemplification of the invention as disclosed in Figures 1 to 5, comprises an extension or arm 17, which is preferably shown integral with the top web 18 of a truck frame, although it may be separately formed and suitably bolted or otherwise secured to the truck frame.

The extension 17 consists of the flared portion 19 shown provided with a reenforcing rib 20. The arm which is of comparative width has a side wall 21 extending downwardly and terminating in the horizontally disposed portion 22 formed parallel with the upper flared end 19 of the extension 17; the horizontally disposed portions adjacent to the side wall 21 being also united by means of the end flanges 23. The bottom portion of the extension 17 is also shown reinforced by means of a web 24 formed integral with the side of the extension or arm provided with the vertical wall 21; the web 24 in the particular exemplification being shown formed integral with the truck frame.

The laterally enlarged horizontally disposed upper and lower portions of the arm are arranged at the outer end of the extension or arm 17 and provide a socket slightly removed from the truck frame, open at the ends and one side to receive the hangers and the keeper elements later to be described. The upper and lower horizontally disposed portions are shown provided with aligned apertures 25 and 26; the aperture 25 in the upper portion being preferably enlarged and made rectangular or non-circular in configuration for the purpose of receiving the head 90 of the bolt 27, after the hanger and keeper elements have been placed in the socket, and turning of the bolt thus prevented.

The keeper means, disclosed in the first five figures of the drawings consists of a pair of 105 complementary plates or members 28 and 29 of suitable thickness to permit the same to be introduced into the socket in the arm as shown

in Figures 1 and 3. The two plates are substantially identical, except that plate 28 is shown chamfered at 30 lengthwise of the intermediate portion between the transverse slots 31, 31, while the plate 29 is provided with a rib 32 adapted to enter the chamfer and thus in conjunction with the intermediate portions 33 and 34 provide a closure for one longitudinal side of the longitudinally arranged groove 35. Both plates at the ends where they are provided with the transverse slots 31 are shown slightly curved at 36 in order to permit the slots 31 to be of sufficient depth to accommodate the enlarged upper eyeleted ends of the U-shaped hanger 15, without necessarily increasing the width of the entire plates, while at the same time permitting the supporting pin 37, which passes through the eyeleted ends of the hanger 15 to be seated in the longitudinal groove 35 of the plates. The supporting pin 37 has its ends resting in the grooves 38 arranged in both ends of both plates in order to provide sufficient bearing for the pin; the groove 38 being in alignment with the intermediate longitudinal groove 35, as clearly shown. The ends of the plate 28, in alignment with the chamfer 30, are also chamfered as shown at 39 to receive the ribs 40 of plate 39. Transverse movement of the plates on each other is thereby prevented.

In order to prevent longitudinal movement of the supporting pin 37, one of the plates, for example plate 28, has its ends provided with the lobes or ears 41, 41 which are adapted to lap the ends of the plate 29 and be disposed across the ends of the grooves 38, as shown in Figure 1.

The plates or members 28, 29 are shown of length greater than the length of the socket in the extension or arm of the truck frame and therefore extend beyond the socket portion as shown in Figure 1. In order to properly seat the complementary keeper elements and firmly hold them in the socket, I have shown both members or plates 28, 29 provided with a right angular boss or shoulder 42 adapted to fit into the closed side of the socket intermediate of the end flanges 23.

In practice, the supporting pin 37 is passed through the eyeleted ends of the U-shape hanger 15 and the pin placed into the groove 35 and end grooves 38, with the U-shape hanger straddling the intermediate portion 55 of the keeper element or plate. The top plate is then placed onto the lower plate and the assembled elements then inserted into the socket in the arm, with the angular bosses 42 inserted into the closed side of the socket, thus bringing the apertures 43, 43 of the two plates into register with the openings 25 and 26 in the arm so that the bolt 27 may be put into place and the nut 44 applied thereto, thereby firmly holding the elements in position but allowing such free oscillatory move-

ment of the hanger as is required in the proper operation of the brakes.

As both plates 28 and 29 are similarly grooved, it is apparent that either plate may constitute the upper or the lower plate, as in either event the lobes 41 will be disposed across the end of the pin-receiving groove and prevent its longitudinal movement as clearly evident from Figure 1. The chamfers and ribs of the two plates provide a non-shifting relation, transversely, between the two plates while the lapping lobes will prevent longitudinal shifting or movement.

This construction of my improved keeper means has been shown in connection with a U-shape type of hanger; but it is apparent that a continuous link type of hanger as shown at 16 in Figure 6 may be employed therewith.

With the type of keeper means shown, it is evident that the supporting pin 37 will have suitable support throughout its length to give it the necessary rigidity for supporting the hanger and brake shoes and that wear resulting from oscillations of the brake hanger will be confined to elements which may be easily replaced as all wear resulting from movement of the pin 37, or oscillations of the continuous type of link 16, will be confined to the plates themselves and therefore the integral extension or arm of the truck frame encounters no wear. The construction, however, is such that assembly of the parts is very easily accomplished.

In Figures 6 to 10, I show a modified form of the keeper means intended especially for use with the continuous link hanger 16, namely in situations where no hanger supporting pin is employed. The keeper and wear receiving means comprises the complementary plates or members 45 and 46 shown in Figures 9 and 10. The keeper members of Figures 9 and 10 are identical with the intermediate portions of keeper members 28 and 29 heretofore described; that is to say, the keeper members 45 and 46 consist of the portions of plates 28 and 29 intermediate of the transverse slots 31, 31. Keeper member 45 comprises a flat block or plate having a transverse groove 47 identical with the groove 35 of the previously described means. The keeper member 45, like keeper 28, is kerfed at 48 to receive the rib 49 of keeper member 46 which likewise consists of a block or plate of dimensions substantially equal to those of block or plate 45. Keeper member 46 is also provided with the longitudinal groove 47; the two semi-circular grooves of the two members when the two plates are arranged one above the other as shown in Figure 7 constitute a channel having a diameter sufficient to receive the end of the continuous link 16 and permit it to have free swinging or oscillatory movement. The two blocks or plates 45, 46, like plates 28 and 29, preferably are each

shown provided with the angular surfaces or bosses 42, 42 which terminate short of the ends of the plates in order to fit into the rear end of the socket formed intermediate of the parallelly disposed upper and lower portions of the extension or arm 17. The keeper members 45 and 46 are each provided with registering holes 43 which will register with the holes 25 and 26 formed in the upper and lower portions of the arm for the purpose of receiving the retaining bolt 27, with the head of the bolt fitting into the non-circular enlarged opening 25 in the top wall of the socket as shown in Figure 7, for the purpose heretofore described. With this construction, like in the previously described construction, all wear resulting from the vibrations and oscillatory movements of the hangers will be confined to the keeper and wear receiving elements 45, 46 and no wear transmitted to an integral portion of the truck frame. It is also apparent that these keeper elements with the hanger may be quickly removed from the socket, to permit renewal when occasion requires; or permit replacement by the keeper members 28, 29 in the event it is desired to substitute the U-shape type of hanger 15 and the supporting pin.

One side of the enlarged portion of the supporting member or arm,—which is off-set from the median line to permit the brake hanger to straddle said portion,—is shown with an enlarged non-circular opening 25 to permit the head or enlarged part of the bolt or its nut to come into contact with the adjacent keeper plate and thus effect a firm clamping relation between the two plates. This is of material importance as it is essential to provide means whereby the plates are held in firm seating relation with each other and also firmly clamped to the arm against vibration and chatter.

I have shown the arm preferably formed with a substantially horizontally disposed slot, but it is apparent that the slot may be differently disposed and that modifications in the keeper means may be made, without, however, departing from the spirit of my invention.

50 What I claim is:

1. In brake hanger supporting means, a pair of plates arranged face to face with said opposing faces grooved lengthwise to provide a hanger and a hanger supporting pin channel, one of said plates at the ends of

the grooves being provided with projecting lips adapted to lap the other plate at the ends of the groove therein.

2. In brake hanger supporting means, a pair of plates adapted to be placed in superposed relation, the opposing faces of the plates being grooved to provide a longitudinally disposed open ended channel, and means at opposite ends of said supporting means for closing the ends of said channel. 60

3. In brake hanger supporting means, a pair of complementary plates adapted to be placed in superposed relation, the opposing faces of the plates being longitudinally grooved to provide an open ended channel 70 therebetween, integral means for closing the ends of said channel, at least one of said plates having slots disposed transversely of the channel for passage of the brake hanger therethrough.

4. In brake hanger supporting means, a pair of plates adapted to be placed in superposed relation and formed to provide a longitudinal channel intermediate of the opposing faces to receive a hanger and a hanger 80 supporting pin and provided with integral extensions at the ends to provide closures for the ends of said channel.

5. In brake hanger supporting means, an arm secured at one end to the frame of a car truck while the outer end is enlarged and off-set from the median line, said enlarged outer end being provided with a slot open at its ends and having registering bolt-receiving openings disposed transversely of the slot, 90 with one of said openings adapted to receive the head or nut of the bolt.

6. In a brake hanger supporting means, a supporting member secured at one end to the frame of a car truck while the outer end is off-set from the median line of the member to permit straddling thereof by a brake hanger and formed to provide an open ended slot, and keeper means, insertible in said slot, formed to provide a longitudinal brake hanger and a hanger supporting pin receiving groove, disposed in the direction of said slot, said off-set portion and the keeper means being provided with registering bolt-receiving openings disposed transversely of the slot and 100 groove with an opening in the off-set portion enlarged to permit an enlarged portion of the bolt to contact with said keeper means.

VICTOR H. HARBERT.
